UNITED STATES PATENT OFFICE.

WILLIAM H. ENGEL, OF KAUKAUNA, WISCONSIN, ASSIGNOR OF ONE-HALF TO THIL-MANY PULP & PAPER COMPANY, OF KAUKAUNA, WISCONSIN, A CORPORATION OF WISCONSIN.

PAPER-MAKING MACHINE.

Application filed April 23, 1922. Serial No. 557,039.

To all whom it may concern:

Be it known that I, WILLIAM H. ENGEL, a citizen of the United States, residing at Kaukauna, in the county of Outagamie and State of Wisconsin, have invented certain new and useful Improvements in Paper-Making Machines, of which the following is a specification.

My invention has reference more particularly to the construction of a paper making machine of Fourdrinier type so that the wire cloth on which the paper is formed may be removed and replaced without the necessity of dismantling the machine.

The invention consists in the features of novelty hereinafter described, illustrated in the accompanying drawings, and particularly pointed out in the claims at the end of the specification.

On the drawings:

Fig. 1 is a side view of approximately one-half of the length of a machine embodying my improvement;

Fig. 2 a similar view of the other half of the machine;

Fig. 3 a top view of the machine with the deckle frame and the top couch roll removed;

Fig. 4 a view taken on the line 4—4 of Fig. 1 showing the breast roll elevated at one side and the Fourdrinier wire in position to be inserted in place in the machine;

Fig. 5 a sectional view on the line 5—5 of Fig. 2;

Fig. 6 a fragmentary view partly in section on the line 6—6 of Fig. 5; and

Fig. 7 a side view of the standard which supports the bottom couch roll at the side of the machine opposite to that shown in Fig. 2.

Referring to the drawings, the reference numerals 1 and 2 indicate the main standards of the shaker section of the machine. These standards, which are alike, are located at opposite sides respectively of the machine and connected together by a tie rod 3. A pair of parallel I-beams 4 and 5 which constitute the main supporting elements of the shaker section have their corresponding ends pivoted respectively to the standards 1 and 2 as indicated at 6, and at their other ends are supported by hangers 7 on the overhanging portions of the standards 8. The hangers 7 are adjustably connected with the

standards 8 so that the outer ends of the I-beams 4 and 5 may be raised and lowered to regulate the pitch of the Fourdrinier wire, and they are also loosely connected with both the standards 8 and the I-beams 4 and 5 in the usual manner so that the customary side shake may be imparted to the Fourdrinier wire for insuring even distribution of the paper pulp thereon. As the side shaking movement is of very limited extent and is applied to the shaker section at the forward end, that is, the end of the machine at which the standards 8 and hangers 7 are located, and as the shaker section is quite long, there is very little effect of the side shaking action at the rear end of the shaker section, and the pivotal connections 6 afford any looseness that may be required at this point.

Each I-beam 4 and 5 has a pair of standards 9 and 10 mounted thereon, the former of which are connected together by a tie rod 11, and these standards together with the standards 1 and 2 support the superstructure of the shaker section. Each standard 1 and 2 has an extension 12 horizontally pivoted to the upper end on a pivot pin 13, said pins being in axial alignment and permitting the necessary pivotal action of the shaker section super-structure when the hangers 7 are adjusted to raise or lower the forward ends of the I-beams 4 and 5, and each extension 12 and each standard 9 and 10 has a hinge cap 14 secured to the upper end by bolts 15.

Extending along each side of the shaker section is a top rail 17, each of which has spaced legs 18, 19 and 20 connected by pivot pins 15 with the hinge caps 14 of the standard extensions 12 and standards 9 and 10 respectively, the three pivot pins 16 at each side of the machine being axial alignment. This pivotal connection along one side of the machine is provided so as to permit the super-structure of the shaker section to be lifted at the opposite side for the purpose of inserting a new Fourdrinier wire as hereinafter more fully explained. The corresponding pivotal connection at the other side is not required for this purpose, but is provided so as to afford uniformity of structure at both sides of the machine whereby the wear occasioned by the shaking of the section will be the same at both sides of the machine.

Each top rail 17 has a plurality of depending hangers 21 which support another rail 22, the latter being adjustable on the hangers 21 by means of the adjusting screws 23, 5 and these rails 22 which are located at opposite sides of the machine, have a series of closely arranged corresponding bearings 24 in which a series of table rolls 25 are journaled. Mounted under the table rolls 25 10 are a series of save-all pans 26 which are carried by hangers 27 depending from the top rails 17, and also by suitable brackets 28 on the legs 18 and 20.

Beyond the standards 1 and 2 and spaced 15 at opposite sides of the machine are standards 29 and 30, the former of which has an extension 31 pivoted thereon on the pivot pin 32, and beyond the standards 29 and 30 and suitably spaced therefrom are the standards 20 33 and 34 located respectively at opposite sides of the machine, and the standard 33 also has an extension 35 pivoted thereon on the pivot pin 36 in axial alignment with the pivot pin 32. The standard 30 extends upward 25 to a higher elevation than the extension 31 of the standard 29 and has a short support 37 secured thereon by bolts 38, while the extension 31 of the standard 29 has a somewhat longer support 39 secured thereon by bolts 40, and these supports 37 and 39 30 are connected together by the tie rod 41.

Posts 42 and 43 are bolted on the extension 35 and standard 34 respectively and extend upwardly therefrom, as shown in Fig. 2, and 35 there is a top rail 44 at each side of the machine, one of which has the opposite ends secured respectively to the support 39 and the post 42, and the other of which has the opposite ends secured respectively to the support 37 and the post 43. These rails 44 are 40 arranged in parallel relation and form substantially a continuation of the top rails 17 but are inclined downwardly from the ends of the latter, as shown in Fig. 2. Hangers 45 extend downwardly from the rails 44 and 45 carry suction boxes 46 and these rails also have corresponding hangers 47 carrying the guide roll 48. A wire guide box 49 is bolted to the posts 42 and 43 at one side thereof, and at the opposite sides of these posts, 50 bearings 50 and 51 are secured by bolts 53 and 54 to the extension 35 and standard 34 respectively and have the bottom couch roll 55 journaled therein. The post 43 and bearing 51 are not bolted directly to the standard 34, but are secured to a plate 114 as shown in Fig. 7 by the bolts 115 which have their heads seated in recesses in the under-side of the plate, and the bearing 51 also 55 has a flange 116 at the side which is bolted to a flange of the post 43. This structure is assembled in this manner to afford a rigid construction of the rail 44 with the bearing 51 for lifting the suction box section of the 60 machine by means of a lever applied to the 65

end of the shaft 103 as hereinafter more fully explained, and this assembled structure is detachably secured to the top of the standard 34 by the bolts 54.

At the forward end of the machine the 70 legs 20 are formed with bearings 56 in which the breast roll 57 is journaled, and the Fourdrinier wire 58 is engaged at the opposite ends over the breast roll 57 and the bottom couch roll 55 respectively, and has the upper length passed over the table rolls 25, suction boxes 26 and the guide roll 48. A pair of guide rolls 59 and 60 are mounted in bearings 61 and 62 respectively on the L-beams 4 and 5 to support the lower length 80 of the Fourdrinier wire, and beyond the shaker section are a pair of wire carrying rolls 63 and 64 which are mounted in bearing standards 65 and 66 respectively which latter are bolted to the floor upon which the 85 machine is mounted.

A stretch roll 67 is mounted between the guide rolls 59 and 60 on a pair of links 68 at opposite sides respectively of the machine, and these links are pivoted at their 90 upper ends to a corresponding pair of links 69 which are pivoted at their upper ends to brackets 70 on the top rail 17 so that the stretch roll 67 is free to drop down onto the lower length of the Fourdrinier wire 95 58, said roll being of sufficient weight to hold the Fourdrinier wire stretched at the required tension for proper operation thereof. In removing the Fourdrinier wire the stretch roll 67 is raised out of engagement 100 with the lower length of the Fourdrinier wire, and held elevated by hangers or hooks 71 on the top rails 17, in which the ends of the shaft of the roll 67 are engaged, 105 as indicated by dotted lines in Fig. 2.

The deckle frame 72 which is of the usual construction, is detachable from the machine and to this end is provided at each side with adjustable supports 73 having convex heads 74 at their lower ends, and the top rails 17 of the machine are provided with corresponding concave recesses 75 to receive the heads 74 of the deckle frame supports 73 for properly positioning and holding the deckle frame on the machine. By thus forming the top rail 17 with recesses to receive the heads 74, I avoid the presence of bolts and other projections above the rail 17, which bolts or other projections would interfere with freely slipping the Fourdrinier wire sidewise over the rails and the rolls, etc., carried thereby. This deckle frame has brackets 76 at the breast roll end of the machine which supports sheaves or pulleys 77 around which the deckle straps 78 are passed, the other end of these straps being passed around sheaves or pulleys 79 carried by brackets 80 which are bolted to the top rails 44. The upper length of the deckle straps 115 120 125 130 between the sheaves or pulleys 79 and the

deckle frame 72 are supported by sheaves or pulleys 81 carried by brackets 82 which are secured by bolts or cap screws to the top rails 17, the lower length of the deckle 5 straps being positioned to rest upon and adapted to travel with the upper length of the Fourdrinier wire 58 as it passes over the table rolls 25. The brackets 76 which support the sheaves or pulleys 77 are secured 10 to the deckle frame by the bolts 83 and 84, the latter being engaged in slots 85 of the brackets 76 so that the latter may be oscillated about the bolts 83 for raising and lowering the sheaves or pulleys 77, such 15 adjustment being regulated by set screws 86 which are interposed between the end of the bracket 76 and a flange 87 of the deckle frame.

A top couch roll which is indicated at 88, 20 bears upon the upper surface of the Fourdrinier wire 58 as it passes over the lower couch roll 55, said roll 88 being journaled in a pair of brackets 89 at opposite sides respectively of the machine, which are pivoted 25 at 90 on the standard 91 so that the top couch roll 88 may be swung from the position of engagement with the Fourdrinier wire to a position such as shown by dotted lines at 92 in Fig. 2, to afford ample clearance 30 between the couch rolls 88 and 55 when it is desired to change the Fourdrinier wire.

Extending between the corresponding legs 18, 19 and 20 at opposite sides of the machine and also between the supports 37 35 and 39 are channel irons 93 which have their ends at the left-hand side of the machine, as the latter is viewed in Fig. 4, secured by bolts 94 to the respective supports 18, 19, 20 and 39, and the opposite ends of these channel irons are secured to the corresponding supports 18, 19, 20 and 37, at the opposite side of the machine by an L-shaped clamp 95 which has one or 45 more threaded arms inserted through the respective support, and secured thereto by nuts 96 which clamp the end of the channel iron 93 in place and afford an unobstructed opening into the end of the channel member.

50 A lifter bar 97 of suitable cross sectional form to fit therein is provided for each channel member 93, and each lifter bar has an arm or extension 98 pivoted at 99 to the outer end thereof, which extension may be held in the extended position against pivotal movement by a locking pin 100 which engages apertures in the adjoining hinge portions of the lifter bar and extension respectively.

55 I have also provided lifting means for the opposite ends of the machine comprising similar socket members 101 which telescope onto the ends of the shafts 102 and 103 of the breast roll 57 and the bottom couch roll 60 respectively, said shafts being extended

beyond their bearings at the right-hand side of the machine as the latter is viewed in Fig. 4, so as to be engaged by said socket members, and each socket member has a lever or arm 104 pivoted to the outer end 70 thereof as indicated at 105, and the inter-engaging hinge portions of the socket member 101 and lever 104 are provided with apertures to receive a pin 106 whereby the socket member 101 and lever 104 are 75 held in alignment and prevented from pivotal movement.

When it is desired to change the Fourdrinier wire, the deckle frame 72 is lifted from the machine and held at a distance 80 above the latter so as to afford ample clearance between the top of the machine and the deckle frame for inserting the new Fourdrinier wire therebetween, and the bearing brackets 80 and 82 are unbolted from the 85 rails 44 and 17 respectively, and these brackets with their sheaves 79 and 81 are likewise lifted and held at a suitable distance above the top of the machine. The upper couch roll 88 is also lifted and held at a distance 90 above the top of the machine substantially in a position shown by dotted lines at 92, and the table board 107 which is hinged to the head box 108, as indicated at 109, is thrown back so that the entire top of the machine 95 is left clear for the insertion of a new Fourdrinier wire. The stretch roll 67 is lifted up and engaged in the hangers 71 as shown by dotted line in Fig. 2; the support unbolted from the standard 30, and the assembled bearing 51, plate 114 and leg 43 unbolted from the standard 34. The three pivot caps 14 at the right hand side of the machine, as the latter is viewed in Fig. 4, are also unbolted from the standards 9 and 10 100 and the extension 12 and the super-structure of the machine is then ready to be lifted for inserting the new Fourdrinier wire. The old wire 58 may be removed at any time as it is customary to cut it, and this of course 105 permits removal of same before the machine is separated at the side.

The lifting bars 97 are now inserted in the channel irons 93, and the sockets 101 inserted on the ends of the shafts 102 and 115 103, as shown in Fig. 3. The levers 98 and 104 are then swung inwardly to positions close against the side of the machine, as shown by dotted lines in Fig. 3, after which the new Fourdrinier wire is stretched out 120 on the floor alongside of the machine. The upper length of the Fourdrinier wire is then lifted and the levers 98 and 104 swung outwardly to the position shown in full lines in Fig. 3, so as to support the new Fourdrinier wire, as indicated at 110 in Fig. 4, and the locking pins 100 and 106 are inserted in place so as to hold the levers 98 and 104 in the out-turned position. The outer ends of all the levers 98 and 104 130

are then connected to a hoist 111 and the hoist operated so as to lift the outer ends of all these levers simultaneously so that the upper portion of the machine swings 5 on the pivots 16—16—16, 32 and 36 at the left-hand side of the machine, as the latter is viewed in Fig. 4, and the parts 14—14—14, 37, 43 and 51 at the right-hand side of the machine are lifted away from 10 the parts 9, 10, 11, 12, 30 and 34 at the right-hand side of the machine, as shown in Fig. 4, so as to leave a gap therebetween through which the lower length of the new Fourdrinier wire 110 may be readily inserted. The new Fourdrinier wire 110 is then pushed laterally into the machine with the ends engaging around the breast roll 57 and the bottom couch roll 55 respectively, and the upper length engaged over the table 15 rolls 25, suction boxes 46 and guide roll 48, while the lower length of the new Fourdrinier wire is inserted between the separated parts of the frame, under the table rolls 25, save all pans 26, stretch roll 67, 20 suction boxes 46, guide roll 48, wire guide box 49 and other parts of the top of the machine, said lower length being inserted 25 over the wire carrying rolls 59, 60, 63 and 64. After the new Fourdrinier wire has 30 been fully inserted, the hoist 111 is operated to lower the outer ends of the levers 98 and 104 so that the members 14—14—14, 37 and plate 114 of the assembled bearing 51 and post 43 rest again on the respective 35 parts, whereby they are supported, dowell pins 112 being preferably provided on these parts to insure return of said parts to the proper position, and the parts 14—14—14, 37 and 114 are then bolted down in place. 40 The lifting members 98 and 104 are then removed, the table board 107 laid down in position and the top couch roll released and lowered into the operative position. The deckle frame 72 is lowered into position with 45 the convex heads 74 of the supports 73 engaged in the concaved recesses 75 and the sheaves 79 and 81 are lowered and their brackets 80 and 82 bolted in place on the side rails 44 and 17 respectively. The 50 stretch roll 67 is then released from the hooks 71 and lowered onto the lower length of the Fourdrinier wire between the rolls 59 and 60, thereby imposing the necessary tension on the wire and the machine is now 55 ready for operation.

From the foregoing it will be observed that the replacement of the Fourdrinier wire is effected without disturbing the table rolls, suction boxes, save all pans, breast roll, 60 lower couch roll, guide roll and various other parts which it has been necessary heretofore to remove when it is necessary to replace the wire, these parts being merely lifted with the upper section of the frame 65 to insert a new wire in place after which

the upper section of the frame is bolted back in place.

While I have shown and described my invention in a preferred form, I am aware that various changes and modifications may 70 be made without departing from the principles of my invention, the scope of which is to be determined by the appended claims.

I claim:

1. In a Fourdrinier paper making machine, the combination with supporting stands, of a roller-carrying frame removably bolted to said stands at one side of the machine frame, and pivot pins extending lengthwise of said roller carrying frame 80 at the opposite side of the machine frame, upon which pivot pins said roller carrying frame is hingedly mounted.

2. In a Fourdrinier machine, the combination of suitable supporting stands, a roller 85 frame hinged at one side of the machine to the stands and adapted to be raised therefrom at the opposite side of the machine to receive the wire, and a series or bars adapted to engage said frame and having outer 90 sections adapted to swing between longitudinally extending and laterally projecting positions.

3. In a Fourdrinier machine, the combination of shaker and suction box sections, 95 each of which comprises a frame hingedly mounted at one side of the machine and detachably supported at the other side, said frames carrying couch, breast and table rolls and suction boxes, and means for lifting said 100 frames at one side on the hinge mounting at the other side for admitting an endless Fourdrinier wire into the machine with the upper and lower lengths of the wire positioned respectively above and below said rolls and 105 suction boxes.

4. In a Fourdrinier machine, a shake frame comprising a lower supporting section and an upper roller carrying section, 110 said sections being hinged together at both sides of the machine and being removably connected together at one side of the machine to permit the upper roller carrying section to be tilted.

5. In a Fourdrinier machine, a shake 115 frame formed of lower and upper sections, said lower section comprising longitudinal beams mounted for vertical adjustment and transverse shaking movement, supporting stands on said beams, said upper frame section comprising side rails and brackets, the latter being removably bolted to the stands at one side of the frame, and pivotal connections having axes extending in longitudinal alignment, said connections being arranged 120 between the brackets and stands at the opposite side of the frame.

6. In a Fourdrinier machine, the combination with supporting stands, of a roller carrying frame tiltably connected at one side 130

of the machine to said stands, a channel bar extending transversely of said frame, said channel bar being bolted to said frame at one side, and a bracket for supporting said channel bar at the opposite side of the frame whereby said channel bar is left open at one end to receive a lifting lever.

7. In a Fourdrinier machine, the combination with supporting stands, of a roller carrying frame tiltably connected at one side of the machine to said stands, a channel bar extending transversely of said frame, said channel bar being bolted to said frame at one side, a bracket for supporting said channel bar at the opposite side of the frame whereby said channel bar is left open at one end to receive a lifting lever, and a lever adapted to be inserted in said channel bar and comprising inner and outer sections hinged together.

8. In a Fourdrinier machine, the combination of a roller carrying frame and supporting means therefor, said frame being tiltably connected at one side of the machine to said supporting means and adapted to be raised therefrom at the opposite side of the machine to receive a wire, and means for lifting one side of the roller carrying frame comprising a part hinged to swing to a position parallel with the roller carrying frame and to swing to a position at substantially right angles thereto.

9. In a Fourdrinier machine, the combination with a roller carrying frame and suitable supporting means therefor, to which supporting means said frame is connected in manner permitting said frame to be raised at one side for providing an opening lengthwise of the machine to receive the Fourdrinier wire, and means for lifting said side of the roller carrying frame comprising a hinged frame-lifter adapted to swing about a substantially vertical axis so as to lie close

alongside of the roller carrying frame but capable of being swung out laterally at right angles to the length of said frame, and means for raising the outer end of said frame-lifter.

10. In a Fourdrinier machine, the combination with a roller carrying frame and suitable supporting means therefor, to which supporting means said frame is connected in manner permitting said frame to be raised at one side for providing an opening lengthwise of the machine to receive the Fourdrinier wire, means for lifting said side of the roller carrying frame comprising a hinged frame-lifter adapted to swing about a substantially vertical axis so as to lie close alongside of the roller carrying frame but capable of being swung out laterally at right angles to the length of said frame, means for raising the outer end of said frame-lifter, and means for holding said frame-lifter in its outward adjusted position during the lifting operation.

11. In a Fourdrinier machine, the combination with a roller carrying frame and suitable supporting means therefor, to which supporting means said frame is connected in manner permitting said frame to be raised at one side for providing an opening lengthwise of the machine to receive the Fourdrinier wire, means for lifting said side of the roller carrying frame comprising a hinged frame-lifter adapted to swing about a substantially vertical axis so as to lie close alongside of the roller carrying frame but capable of being swung out laterally at right angles to the length of said frame, and means for raising the outer end of said frame-lifter, said frame-lifter being formed of hinged sections, the inner section being adapted to interlock with the roller carrying frame.

WILLIAM H. ENGEL.
